MECHANISM FOR ADDRESSING AND APPLYING POSTAGE STAMPS TO MAILING PIECES

Evert F. Johnson, Oil City, Pa., assignor to The Pennzoil Company, Oil City, Pa., a corporation of Pennsylvania

Application December 18, 1947, Serial No. 792,470

3 Claims. (Cl. 216—1)

1

This application is a continuation in part of my copending parent application, Serial No. 777,203, filed October 1, 1947, which relates to apparatus for effecting systematized customer notification service, the apparatus including, inter alia, a mechanism for applying an address and a postage stamp to a mailing piece and a record card (which forms the subject of my co-pending application, Serial No. 784,912) cooperative with the mechanism and with the mailing piece. The term "mailing piece" is defined in my parent application, and herein, as comprehending post cards, pamphlets and folders to be directly stamped and addressed and envelopes containing mail matter, each of which items has the usual spaces for the postage stamp and the address.

The invention relates to improvements in the mechanism for applying the address and the postage stamp to the mailing piece; and also to improvements in the specific features of correlation, in an operative capacity, between the record card and said mechanism. The record card includes a panel of stencil material and the address applying element of the mechanism includes features which cooperate with the panel.

The principal objects are to provide for automatically setting the mechanism in operation by the insertion in proper relation to it of a unit composed of a record card and an associated mailing piece, to provide for the automatic co-operation of the mechanism with the unit in the application to the mailing piece of the address and the stamp, to provide for the automatic transfer of the unit and the address and stamped mailing piece to delivery position such that the record card and mailing piece may be removed by the clerk and to provide for the automatic resetting of the elements of the mechanism to normal position in which they remain inactive and in readiness for the insertion of another record card and mailing piece whereupon the cycle of operations is automatically repeated.

The mechanism is preferably mounted within a cabinet which encloses an automatic follow-up card file holding and designating machine and other elements of the apparatus (all shown and described in detail in my said parent application, Serial No. 777,203). The elements of the mechanism are accordingly shown in the drawings in connection with such cabinet.

In the drawings:

Figure 1 is a front elevation of the cabinet with its cover elements in closed position.

Figure 2 is a side elevation of the cabinet with its cover elements in open position and the drawer element (which carries the mechanism for apply-

2

ing the address and stamp to the mailing piece) in its outer or open position.

Figure 3 is a perspective view of a record card with an associated mailing piece shown in broken lines, the record card and the mailing piece being shown as combined as a unit and in readiness for insertion in operative relation to the address and stamp applying mechanism.

Figure 4 is a plan view of the record card and associated mailing piece as inserted into operative relation to the address and stamp applying mechanism, parts of the mechanism being shown in horizontal section in the plane 4—4 of Figure 6, looking in the direction of the arrows.

Figure 5 is a diagram of the circuit for the operation of the address and stamp applying mechanism.

Figure 6 is a view in front elevation of the drawer element and the address and stamp applying mechanism as mounted within it, the drawer element being partly broken away to show details of the mechanism and a hinged panel of the drawer element being shown in open position.

Figure 7 is a side elevation of the address and stamp applying mechanism as mounted in the drawer element, the latter being shown in vertical longitudinal section.

Figure 8 is a rear elevation of the address and stamp applying mechanism.

Figure 9 is a detail vertical longitudinal sectional view of the address and stamp applying mechanism in the plane 9—9 of Figure 6, looking in the direction of the arrows, this figure showing more particularly various features of the address applying element of the mechanism.

Figure 10 is a detail vertical longitudinal sectional view of the address and stamp applying mechanism in the plane 10—10 of Figure 6, looking in the direction of the arrows, this figure showing more particularly various features of the stamp applying element of the mechanism.

Figure 11 is a detail horizontal sectional view in the plane 11—11 of Figure 6, looking in the direction of the arrows.

Figure 12 is a perspective view of a supporting plate for various elements of the mechanism with certain parts also shown in perspective.

Figure 13 is an elevation of certain gear elements employed in the operation of the mechanism with certain parts shown in full lines and other related parts indicated in broken lines.

The cabinet C includes a rectangular body 1 having side, front and rear walls, a rectangular bottom supporting flange 2, and a cover composed of elements 3 and 4 hinged to the rear and front walls respectively, normally closed as in-

dicated in Figure 1 and having open positions as shown in Figure 2, the element 4 in open position serving as a desk. The cabinet includes a drawer element 8 having L-shaped side walls composed of vertically extending portions 9 and horizontally extending portions 10, and a front wall 11 which includes an upper panel 12 hinged to one of the vertical portions 9.

The address and stamp applying mechanism A and associated parts are mounted within the drawer element 8 between the vertically extending portions 9 of the side walls and also between lower and upper horizontal plates 167 and 168 provided along their longitudinal edges with angular flanges 169 by means of which they may be attached in any suitable manner to the wall portions 9, the plates 167 and 168 connecting and mutually bracing the wall portions 9 and completing the structure of the drawer element 8.

The elements of the mechanism A are directly supported by a vertically planar transverse plate 170, the vertical edge portions of which are attached, preferably by screws 171, to the inner faces of the co-planar flanges of angle brackets 172 which in turn are secured, preferably by welding, to the side wall portions 9 of the drawer element 8. The plate 170 adjacent its front face supports the elements of the address and stamp applying mechanism and adjacent its rear face supports an associated motor and gearing.

The plate 170 is provided with a horizontal shelf 173 which projects forward from its front face and supports the unit (Figure 3) composed of the record car R and an associated mailing piece M, the elements of the unit in coordinated association being in cooperative relation to the elements of the mechanism A. The shelf 173 is provided on its upper face with shoulders 174 and 175 in right angular relation, the shoulder 174 being parallel to the plate 170 and the shoulder 175 extending forward from the inner end of the shoulder 174. The shoulders 174 and 175 constitute an L-shaped positioning guide for the record card to insure its proper location in cooperative relation to the elements of the mechanism A.

Access to the mechanism A for the purposes of replenishing ink, inserting a new roll of stamps, and lubrication is provided for by the hinged upper panel 12 of the drawer element front wall 11, the panel 12 being provided on its inner face with a latch 176 by which it may be held in closed position and which cooperates in the usual manner with a keeper which may consist of a flange 176a forming a part of the frame of the drawer element 8. The panel 12 has on its outer face and adjacent its free vertical edge a knob 177 by means of which it may be conveniently opened and closed.

The record cards R are, as to the items which are endorsed upon them, used in relation to corresponding "service" cards, illustration of which herein is unnecessary but which are shown and described in detail in my said parent application, Serial No. 777,203. Each record card in its mechanical aspect and in its physically functional relation to the elements of the cooperative combination which distinguishes the invention consists of two major (outer and inner) integrally connected sections 155 and 156 delimited by a common folding line 157. Each record card, qua card record, has vertical blank columns headed by appropriate titles or captions and sub-divided horizontally to provide, for dat-

ing purposes, squares to be filled in by the clerk with pertinent data (all as shown and described in detail in my co-pending application, Serial No. 784,912). The section 155 has at one end a co-planar projection 158 which bears the name of the customer. The apparatus of the invention with which the record card is in physical cooperation may be used in any enterprise where systematized customer notification service is desirable.

It may be assumed, by way of example, that the record card is used in establishments which serve the needs of motor car drivers, i. e. garages, filling stations and similar establishments. The service cards, above mentioned, are filed in the pockets of the filing machine, illustration of which herein is unnecessary but which is shown and described in detail in my said parent application, Serial No. 777,203. As therein set forth the sections 155 and 156 have certain columns which provide for the recording of the number of the pocket of the filing machine in which the corresponding service card may be filed at a time contemporaneous with the last entry on the record card.

The projection 158 constitutes an identification tab which enables the convenient selection of the record card from the cabinet in which it may be filed and its convenient removal. The section 156 has a rectangular window 159 covered by a panel 160 of suitable stencil material. The section 156 also has at its upper end an extension 161 to which it is connected by a transverse folding line 162. The extension 161 is provided for the protection of the panel of stencil material, for the protection of the adjoining record card, for carrying any printed instructions which may be required, and for convenience in effecting the removal of the record card at the completion of its ejective movement by the address and stamp applying mechanism. When the record card is in the filing cabinet the extension 161 is folded upon the section 156 in order to protect the panel of stencil material from dust or smearing. The extension 161 preferably bears upon its face which becomes its inner face when the extension is folded a coating 163 of any suitable varnish occupying a suitable rectangular area, the purpose of which is to prevent the extension 161 from adhering to the ink impregnated panel 160 and to prevent the ink adhering to said panel from seeping through the thin card board of which the extension 161 is composed and smearing the surface of the section 155 of the adjacent record card. In the folded relation of the parts the section 155 protects the opposite face of the stencil panel 160 against dust and smearing.

The upper edge of the section 155 may be regarded as marked off by a printed line and the upper edge 165 of the section 156 and the folding line 162 coincide with such printed line whereby, with the parts in folded relation, the projection 158 extends as a tab beyond the upper edge of the card. The section 156 at its lower edge and adjacent the folding line 157 has a cutaway portion which provides a recess 166.

The mailing piece has the usual spaces for the postage stamp and address. The record cards in their mechanical aspect as a part of the unit which includes the mailing piece M have features by virtue of which they are at once coordinated to the mailing piece and to the elements of the mechanism A as will be hereafter set forth in detail. In the use of the record cards

for the stamping and addressing of mailing pieces the sections 155 and 156 are folded one upon the other with the data bearing side of the section 155 exposed. The mailing piece M (broken lines, Figure 3) is inserted between the sections 155 and 156 to the extent limited by its engagement with the meeting edges of the sections as connected along the folding line 157. In such insertion the stamp bearing portion is located in registry with the recess 166, the right angularly related edges of the mailing piece which the stamp bearing portion adjoins are respectively coincident with the meeting edges of the sections 155 and 156 (i. e., the folding line 157) and the free edge of the section 156 which extends forward from the recess 166 and the address located in contacting engagement with the meeting edges of the bearing portion is located in registry with the panel 160.

Let it be assumed that the customer is to be notified of service needed. His record card shows whether there has been any previous contact. The information supplied by the service and record cards considered in combination enables the clerk to determine the character of notification required and the identity of the particular mailing piece to be sent. The date of notification and a description of the particular mailing piece are then entered in the appropriate squares. The mailing piece M is then inserted between the folded sections 155 and 156 in the manner above described.

The unit composed of the record card and the associated mailing piece is inserted (as herein-after described) upon the shelf 173 in immediate cooperative relation with the elements of the mechanism A through a horizontal slot 178 in the front wall of the drawer element 8 and is partially ejected (by the movable address applying elements) through an angular slot continuation 179 in the vertical wall 9 at which the slot 178 terminates, the record card extension 161 being introduced into the slot 179 when the unit is inserted upon the shelf 173. The slot 178 is formed by cutting away the lower edge of the panel 12 and may be bounded by a U-shaped reinforcing frame 180, one element of which is attached to the panel 12 and the other element of which is attached to the upper edge of the section of the front wall 11 below the panel 12.

The elements of the mechanism A are normally maintained in inoperative relation whereby the elements above the shelf 173 are spaced from the shelf to provide a clearance into which the record card may be inserted. The shoulder 174 guides the record card through the machine and the movement of the record card, as guided by the shoulder, is lineally coincident with the shoulder. The record card is inserted upon the shelf 173 in a direction at right angles to the shoulder 174 and is guided in its insertion upon the shelf 173 by the shoulder 175. As thus inserted upon the shelf 173 the record card engages the finger 215 (to be later described in detail) and thereby initiates the operation of the motor 209 (Figure 5) with resultant successive operations of the stamp applying mechanism and the address applying mechanism, the latter also serving to move the record card in the direction of the shoulder 174 and to effect the ejectile movement of the record card, as guided by the shoulder 174, from the machine.

When the address and stamp applying mechanism is to be used the clerk moves the cabinet

cover elements 3 and 4 and the drawer element 8 to open positions. The drawer element in its open position enables the insertion of the unit composed of the record card and the mailing piece into operative relation with the mechanism and enables the unit to be moved through the slot 179 to ejectile position. The open drawer element 8 also provides additional support for the open cover element 4 when used by the clerk as a desk in connection with the association of the mailing piece with the record card and making date entries on the record card.

The stamp applying device, indicated generally as 181, may be of any suitable known construction (for example as shown in Patent No. 1,877,849, issued September 20, 1932) which includes an actuating plunger 182 projecting beyond the casing 183 of the device and normally held in projected relation, the plunger 182 being pushed inward in order to cause the application of the stamp to the mailing piece and being automatically raised by its loading spring when released, all as taught in the patent above identified. The casing 183 includes a bottom plate 184 and the shelf 173 is provided with a raised platform 185 upon which the plate 184 is supported. The platform 185 provides the shoulder 175 above described and is formed with an upwardly projecting forwardly extending flange 186 parallel to the shoulder 175. A groove 187 is formed in the inner face of the flange 186, the bottom wall of the groove being flush with the surface of the platform 185 and the upper wall of the groove being provided by a portion 188 which overhangs the platform 185 and is a part of the flange 186. The plate 170 is provided with a forwardly projecting lug 190 having its inner vertical face provided with a groove 191 which confronts and is co-planar with the groove 187, the bottom wall of the groove 191 merging with the upper face of the rib 189 which provides the shoulder 174. The stamp applying device 181 is supported directly by the platform 185, the rib 189 and the lug 190, its bottom plate 184 resting upon the platform 185 and upon the upper face of the rib 189 and its end edge portions fitting within the grooves 187 and 191. Thereby the stamp applying device is accurately positioned and is positively held against canting or upward displacement. The stamp applying device 181 is a self-contained unit which may be removed and replaced at will. As positioned upon the platform 185, the rib 189 and the lug 190, the stamp applying device is normally held against outward displacement by a spring finger 181a secured to and projecting forward from the plate 170.

The address applying device includes upper and lower roller quadrants 192 and 193 mounted on shafts 194 and 195 respectively. The upper quadrant 192 is provided with a facing 196 of suitable absorbent ink carrying and applying material and is movable in relation to an ink roll 197 arranged in contacting arrangement above it and at the lower end of an ink reservoir 198. The ink is viscid and the reservoir 198 is provided with a gravity operated ink forcing plunger 199 having a guide stem 200 which projects through a central opening in the cap 201 by which the upper end of the reservoir 198 is closed, the cap being freely removable from the reservoir whenever the supply of ink is to be replenished.

The reservoir 198 is carried by a supporting sleeve 202 with which it is preferably formed in-

tegral. The plate 170 is provided with a forwardly projecting block 203 having an opening 204 which extends through the plate 170 and in which the sleeve 202 is fitted, the sleeve being secured by a screw 205 tapped into the block 203. The sleeve 202 provides a bearing for a shaft 206 which carries the inking roller 197, the reservoir 198 having in its bottom a diametrical opening which is occupied by the inking roller, and the sleeve 202 having a bottom opening 207 through which the inking roller is exposed for contacting engagement with the absorbent facing 196 of the quadrant 192.

The quadrant 193 is mounted below the shelf 173 and a marginal recess 208 is formed in the shelf to accommodate the peripheral portion of the quadrant 193 during its operative movement, such peripheral portion in its operative phase being at least flush with, and preferably slightly above, the upper surface of the shelf 173. The quadrants 192 and 193 are normally in a position in which their adjacent ends are spaced, thereby to provide for the convenient introduction between them of the record card with an interposed mailing piece. The quadrants 192 and 193 are operatively movable through a full circle, the quadrant 192 being movable clockwise and the quadrant 193 being movable counter clockwise. The quadrants are initially so positioned that their peripheral surfaces will not engage the record card until after the operation of the stamp applying device has been completed at which time the quadrants seize the record card R and cooperate with the panel 190 of stencil material to effect the addressing operation. In such operation the quadrants 192 and 193 also move the record card to partially ejected position. When the ejective movement of the record card has been completed the quadrants will have returned to their normal inactive positions and will have released the record card. The record card is guided in its ejective movement by the shoulder 174. Its extension 161 at all times projects through the slot extension 179. In its partially ejected position the record card projects through the slot extension 179 and the extension 161 may be readily grasped by the operator in effecting the complete removal of the record card from the drawer element 8.

The stamp and address applying devices are operated by a motor 209 through suitable gearing designated generally as 210. The motor 209 is normally idle and is operative only during the period when the record card with its interposed mailing piece is in association with the mechanism A, the operation of the motor being automatically initiated by the record card and being continued throughout the period of movement of the record card as effected by the quadrants 192 and 193.

The circuit of the motor 209 (Figure 5) is controlled by a normally open switch designated generally as 211, preferably of the micro-type, which is closed, and held closed, by the record card. The switch 211 carries an externally mounted leaf spring 212 connected to a movable contact element 213 within the switch casing. The spring 212 normally assumes a position in which the contact 213 is disengaged from its companion stationary contacts 214. At its free end the spring 212 carries an upwardly projecting finger 215 extending through an opening 216 in the shelf 173 and communicating with a recess 217 in the shoulder 174. The finger projects beyond the upper face of the shelf 173 and into the path of

the record card as inserted into operative relation between the normally inactive elements of the mechanism A. The record card is inserted upon the shelf 173 in a direction at right angles to its path of movement through the machine as prescribed by the shoulder 174 and in such insertion its folded edge engages the finger 215 and moves it into the recess 217, the finger 215 thereby effecting the inward movement of the spring 212 and the engagement of the contact element 213 with the contacts 214 with resultant closure of the circuit of the motor 209. This circuit includes lines 218 and 219 connected to the respective power lines 76 and 77 and, in series, connected by the motor features and terminating in the contacts 214.

The block 203 is provided with an opening 220 which extends through the plate 170 and in which the shaft 194 is journaled. The plate 170 is also provided with a forwardly projecting block 221 located adjacent the underface of the shelf 173 and in vertical alignment with the block 203, the block 221 being formed with an opening 222 which extends through the plate 170 and provides a journal for the shaft 195. The quadrants 192 and 193 are mounted fast upon the portions of the shafts 194 and 195 which project forward beyond the blocks 203 and 221. The shafts 194 and 195 are symmetrically located with reference to the shelf 173 and project inwardly beyond the plate 170.

The plunger 132 of the stamp applying device 121 is automatically operated, that is to say depressed and released for return movement, by a vertically movable slide 223 having at its upper end a forwardly projecting arm 224 which overhangs and engages the upper end of the plunger 132 (the arm 224 being shown in plan in Figure 11 in dot and dash lines). The slide 223 is movable in a vertical slot 225 formed in the plate 170 and open to its upper edge, the slide being guided in its vertical movement and held against displacement from the plate. For these purposes the slide is formed on its side face with grooves 226 into which the portions of the plate 170 adjacent the vertical walls of the slot 225 project.

The plate 170 forms a wall of a gear casing 227, the other wall of which is provided by a plate 228 located in spaced relation behind, and supported by, the plate 170, the plate 228 in turn providing direct support for the motor 209. For the support of the plate 228 the plate 170 is formed with a number of suitably located rearwardly projecting lugs 229 to which the plate 228 is attached by screws 230.

The casing of the motor 209 is provided at its sides with angle brackets 231 which are attached by screws 232 to the plate 228 adjacent its rear face. The projecting end of the shaft 233 of the motor 209 carries a worm 234 which meshes with a worm wheel 235 mounted on a shaft 236. The reduction gearing which includes the worm 234 and the worm wheel 235 is otherwise mounted in the gear casing 227 and its various elements serve for the operation of the quadrants 192 and 193, the inking roller 197 and the slide 223.

The worm wheel shaft 236 carries within the gear casing 227 a pinion 238 which meshes with a substantially larger pinion 239 mounted upon an arbor 240 supported by the plate 228. The pinion 239 has attached to it a cam 241 arranged in the space between it and the plate 170, the cam being movable through a single revolution in its operative phase. The slide 223 is provided at its lower end and within the gear casing with a laterally projecting roller 242 which is engaged by

the active surface of the cam 241. As viewed in Figure 8 (broken lines) the rotation of the cam 241 is clockwise and in such rotation the cam, acting on the roller 242, depresses the slide 223 with resultant depression of the plunger 182 in its stamp affixing operation. When this operation has been completed the cam 241 passes beyond the roller 242 whereupon the plunger 182 is raised by its spring (not shown) and as it moves to its upper position raises the slide 223, returning it to its normal elevated position in which the roller 242 is positioned for another engagement by the cam 241.

At the inner side of the plate 170 the shafts 194 and 195 carry meshing pinions 243 and 244 located within the gear casing 227 and of equal diameters whereby the shafts will be driven at equal speeds and in opposite directions. The upper shaft 194 also carries a pinion 245 of the same diameter as, and in mesh with, the pinion 239 which, therefore, serves not only for the operation of the cam 241 but also, through the gears 245, 243 and 244, for the operation of the quadrant shafts 194 and 195.

The shaft 206 which carries the inking roller 187 projects beyond the inner side of the plate 170 and carries a small pinion 246 in mesh with and driven by the pinion 243. Thereby the pinion 243 in addition to rotating the shaft 194 and effecting the operation of the quadrant 192 also, during each operation of the quadrant, causes a number of revolutions of the inking roller 187 whereby the ink will be effectively and uniformly distributed upon the absorbent facing 196 of the quadrant 192 during each operation of the quadrant.

Summarizing the operative characteristics of the machine: The stamp and address applying mechanisms are operative, cyclically, by a motor which is normally at rest and their active elements are normally spaced above the shelf 173 to permit the insertion of the record card upon the shelf in a direction at right angles to its path of movement through the machine as prescribed by the shoulder 174. Upon such insertion the folded edge of the record card trips the finger 215 and initiates the operation of the motor which, through the gearing described, effects the successive operations of the stamp applying mechanism and the address applying mechanism, the latter by direct cooperation with the record card feeding the unit composed of the record card and its interposed mailing piece through the machine and effecting the ejectile movement of the unit. When the record card passes beyond the finger 215 the spring 212 automatically resets the finger and disconnects the motor, the finger being so located that when the motor is thus disconnected the operating parts have returned precisely to their normal positions as above described.

I claim:

1. Mechanism for applying an address and a postage stamp to a mailing piece fitted within a stencil bearing holder, comprising, in combination, a horizontal supporting shelf for the holder, a reciprocatorily movable stamp applying element located above the shelf and having an operating cycle of movement which includes its movement toward the shelf and in the discharge of its stamp applying function and its movement away from the shelf into an inoperative position in which it is normally maintained, a pair of companion roller elements located respectively above and below the shelf and cooperative with one another in the operations of printing an address upon the mailing piece and effecting the ejectile

movement of the holder, the upper roller element being in the form of a quadrant and having an operating cycle of a revolution, the upper roller element being provided with an ink applying feature, the shelf having a recess through which the surface of the lower roller element is exposed for cooperation with the holder, the shelf also having in right angular relation a transverse guide shoulder and a longitudinal guide shoulder, said guide shoulders being cooperative with the holder, a motor, and gearing operated by the motor for simultaneously moving the stamp applying element and the roller elements through their operating cycles, the printing operation of the roller elements succeeding the operation of the stamp applying element and the roller elements in their printing operation also cooperating to effect the ejectile movement of the holder along the shelf in the direction prescribed by the longitudinal guide shoulder.

2. Mechanism for applying an address and a postage stamp to a mailing piece fitted within a stencil bearing holder, comprising, in combination, a horizontal supporting shelf for the holder, a reciprocatorily movable stamp applying element located above the shelf and having an operating cycle of movement which includes its movement toward the shelf in the discharge of its stamp applying function and its movement away from the shelf into an inoperative position in which it is normally maintained, a pair of companion roller elements located respectively above and below the shelf and cooperative with one another in the operations of printing an address upon the mailing piece and effecting the ejectile movement of the holder, the upper roller element being in the form of a quadrant and having an operating cycle of a revolution, the upper roller element being provided with an ink applying feature, the shelf having a recess through which the surface of the lower roller element is exposed for cooperation with the holder, the roller elements in cooperative relation grasping the holder and simultaneously effecting the printing operation and the ejectile movement of the holder along the supporting element, a motor, and gearing operated by the motor for simultaneously moving the stamp applying element and the roller elements through their operating cycles, the printing operation of the roller elements succeeding the operation of the stamp applying element and the roller elements in their printing operation also cooperating to effect the ejectile movement of the holder along the shelf.

3. Mechanism as set forth in claim 2 wherein the motor element is electrically driven and is controlled by a normally open switch having a movably mounted actuating finger normally projecting into the path of the holder as it is initially placed upon the shelf, the finger thereby being movable by the holder into position to close the circuit of the motor and returning to its normal position when it is released by the holder in the course of its ejectile movement.

EVERT F. JOHNSON.

EVERT F. JOHNSON

It is hereby certified that error appears in the printed specification of the above numbered patent requiring correction as follows:

Column 1, line 34, for the word "address" read *addressed*; column 5, lines 17 and 18, strike out "located in contacting engagement with the meeting edges of the";

and that the said Letters Patent should be read as corrected above, so that the same may conform to the record of the case in the Patent Office.

Signed and sealed this 30th day of January, A. D. 1951.

[SEAL]

THOMAS F. MURPHY,
Assistant Commissioner of Patents.
